UNITED STATES PATENT OFFICE.

WILLARD A. PETTEYS, OF WILCOX, NEBRASKA.

GRAIN CLEANER, SEPARATOR, AND DRIER.

1,345,230.

Specification of Letters Patent. Patented June 29, 1920.

Application filed May 3, 1919. Serial No. 294,387.

To all whom it may concern:

Be it known that I, WILLARD A. PETTEYS, a citizen of the United States, residing at Wilcox, in the county of Kearney and State 5 of Nebraska, have invented certain new and useful Improvements in Grain Cleaners, Separators and Driers, of which the following is a specification.

This invention has for its object to provide 10 an apparatus for the treatment of grain including a novel type of hood provided with a series of internal baffles over which the grain is caused to travel and which is provided with relatively adjustable groups 15 of ventilating shutters which may be opened to admit air to facilitate drying of the grain.

Another object is the provision of an apparatus of this character in which the grain 20 from the ventilating hood is directed into a receiving hopper over a separating screen by which the foreign matter is separated from the grain and conducted to a separate discharge spout in the receiving hopper.

With the above and other objects in view, 25 as will appear as the description proceeds, the invention comprises the various novel features of construction and arrangement of parts which will be more fully described 30 herein and set forth with particularity in the claims appended hereto.

Reference is had to the accompanying drawings forming a part of this application, in which like reference characters indicate 35 the corresponding parts throughout the several views, in which—

Figure 1 represents a front elevation, partly in section and partly broken away of the improved cleaning, separating and 40 drying device,

Fig. 2 represents a perspective view of the receiving hopper detached,

Fig. 3 represents a vertical sectional view through the ventilating hood, and

Fig. 4 represents a vertical sectional view 45 through the receiving hopper.

Referring to the drawings in detail, where- 50 in similar reference numerals designate cor- responding parts throughout the several views, the numeral 5 indicates generally the ventilating hood which consists essentially of front and rear walls 6 and a top 7 hav- 55 ing a hinged section 8 facilitating access to the interior of the hood. The sides of the hood are open and the front and rear walls are maintained in spaced relation by bolts

9 to which the pulley supports 10, to be hereinafter more fully described, are attached.

The upper portion of the rear wall of the 60 hood is formed with an inlet opening 11 through which grain is introduced into the interior of the hood and a series of inclined and staggered baffle plates 12 is arranged beneath the opening 11 and is designed to 65 cause the grain to pursue a circuitous course through the hood.

A series of hinge rods 13 is secured to the opposed edges of the front and rear walls and pivotally support groups of ventilating 70 shutters 14. The shutters, when closed, lie in overlapping relation, as clearly shown in Fig. 3, to prevent the entrance of water into the hood and, as the baffles 12 are arranged in spaced relation air is permitted 75 to circulate through the hood to accelerate drying of the grain flowing therethrough.

A pair of pulleys 15 is supported at the outer terminals of the supports 10 and cables 16 are arranged thereover. 80

The front terminals of the several hinge rods 13 are directed angularly as at 17 and the angular terminals of each group of ventilating shutters are arranged in parallel relation and are connected by a rod 18 where- 85 by the several shutters are caused to move in synchronism. One of the hinge rods of each group is also extended rearwardly of the hood 5 and is directed angularly and connected with one of the cables 16 for con- 90 venience in adjusting the shutters to control the passage of air through the hood.

The lower open discharge end 20 of the hood is supported upon and communicates with an inclined chute 21 the lower terminal 95 of which is supported upon the receiving hopper 22 and a separator screen 23 is ar- ranged within the chute 21 above the in- clined bottom thereof and extends upwardly beneath the discharge opening in the hood 100 100 whereby the grain discharged therefrom is deposited upon the screen and moved down- wardly thereon by gravity.

The receiving hopper 22 is provided with a vertical internal partition 23^a dividing the 105 interior of the hopper into the chambers 24 and 25. The lower edge of the separator screen 23 is extended over the top edge of the partition 23^a whereby the clean grain is directed into the chamber 24 and is con- 110 ducted therefrom through a laterally pro- jecting discharge spout 26. The dirt and

other foreign matter which falls through the separator screen 23 and moves downwardly upon the inclined bottom of the chute 21 is deposited in the chambers and is conducted therefrom through the discharge spout 27.

What I claim is:

1. In a device of the character described, a receiving hood having a receiving opening therein, a plurality of inclined and staggeredly arranged baffles arranged in the hood beneath the opening therein, hinge rods arranged in the hood groups of ventilating shutters hingedly supported upon the rods in the opposite sides of the hood to control the passage of air therethrough, one hinge rod at each group being extended and directed angularly, operating means connected with the angular terminals of the rods, and means connecting the opposite ends of the rods of each group whereby simultaneous adjustment of the several shutters of each group is affected.
2. In a device of the character described, a hood provided with ventilating openings, hinge rods arranged transversely of the openings, opposed groups of shutters piv-

otally supported upon said rods and normally retained in closed position by gravity, one rod of each group being directed angularly, a flexible operating element having its terminals connected with the angular terminals of said rods, the opposite terminals of the rods of each group being directed oppositely to the first mentioned angular terminal, and means connecting the last mentioned angular terminals of the several rods of each group whereby the shutters of such group are simultaneously adjusted.

3. In a device of the character described, a hood including front and rear walls and provided with open sides and bottom, one of said sides having a receiving opening in the upper portion thereof, hinge rods extending between and maintaining the front and rear walls in spaced parallel relation, and opposed groups of shutters carried by the rods and adapted, when closed, to lie in overlapping relation to form closures for the open sides of the hood.

In testimony whereof, I affix my signature hereto.

WILLARD A. PETTEYS.
